A. B. STARR.
BOTTOMING MACHINE.
APPLICATION FILED OCT. 2, 1913.

1,106,419.

Patented Aug. 11, 1914.

UNITED STATES PATENT OFFICE.

ALDEN B. STARR, OF NEW YORK, N. Y.

BOTTOMING-MACHINE.

1,106,419.

Specification of Letters Patent. Patented Aug. 11, 1914.

Application filed October 2, 1913. Serial No. 792,929.

To all whom it may concern:

Be it known that I, ALDEN B. STARR, a citizen of the United States, residing at the city of New York, borough of Manhattan, and State of New York, have invented certain new and useful Improvements in Bottoming-Machines, of which the following is a full, clear, and exact description.

This invention relates to bottoming machines especially adapted for fixing the bottoms in receptacles, such as paper cartons and the like.

Certain machines of this character comprise an intermittently-rotating dial upon which are mounted a plurality of mandrels. The open-ended tubes which constitute the side walls or body of the receptacle are placed over these mandrels, which are then revolved to bring them in turn into operative relation with suitable mechanism for emplacing the bottoms within bodies of the receptacles carried thereby.

Attempts have been made heretofore to remove the finished receptacle from the mandrel by directing a compressed fluid medium against the inner surface of the bottom of the receptacle, but the manner in which this has been accomplished has possessed certain inherent objections, chiefly due to the formation of the passages for the fluid medium in the mandrel proper. These passages frequently become clogged from various causes and in order to clear them, it is necessary to remove the mandrel from its supporting dial. Considerable care and extreme accuracy is required to reset the mandrel upon the dial, so that, on rotation of the dial, the mandrel will again be brought into exact vertical alinement with the mechanism for fixing the bottom within the body portions.

The object of my invention is to overcome this objection and to thereby eliminate the loss of time and labor spent in resetting the mandrel on the dial, and with this object in view, my invention consists of means for directing the compressed fluid medium against the bottom of the receptacle, which means shall comprise a unitary structure, separate and distinct from the mandrel and adapted to be placed over the outside thereof so that it may be easily removed therefrom without removing the mandrel from the dial.

My invention also consists of the combination of this improved structure for directing the fluid medium with a novel form of mandrel and appurtenant parts as will be

set out in the specification and claims appended hereto.

In the drawings, Figure 1 is a central longitudinal section of a mandrel on the line 1-1 of Fig. 3, showing my improved structure; Fig. 2 is a detail sectional view on the line 2-2 of Fig. 3; Fig. 3 is a plan view of the structure with the plunger die removed and a portion of the expanding die broken away to show the ends of the tubes for carrying the compressed fluid; and Fig. 4 is a detail of the connections through the dial to the tubes for carrying the compressed fluid.

In the drawings, a hollow cylindrical mandrel 1, of a size to receive the open-ended tube 2 which forms the side walls or body of the receptacle, is supported on an intermittently-rotating dial 3, only a portion of which is shown. The mandrel 1 is provided with a flange 4 by which the mandrel is fastened to the dial by screws 4', and surrounding the lower end of the mandrel is an annular collar 5 which forms the base for the tube 2. The tube 2 is maintained rigidly positioned with respect to the mandrel 1 by an expanding die consisting of four sector-like jaws 7, the outer faces of which are shaped to the curvature of the tube and provide a broad bearing surface, which, when the jaws 7 are moved outwardly, firmly grip the interior surface of the tube 3 and clamp the same to the mandrel. The jaws 7, which slide on the top of the mandrel, are retained in place thereon by an annular plate 8 which is fastened to the mandrel by bolts 9 passing through elongated slots 10 in the sector-shaped jaws. The portion of the bolts 9 which pass through the slots 10 are provided with anti-friction roller-sleeves 11. The inner ends of the sector-shaped jaws 7 are curved and beveled to provide a conical recess 12. A sleeve 13 is provided with a coned end which engages with the walls of conical recess 12 in the manner of a clutch, the sleeve being slidably mounted within the hollow mandrel 1 which forms a bearing therefor. The mechanism for moving the sleeve 13 upwardly to force the jaws 7 apart comprises a roller 14 carried by the lower end of the sleeve, which end is extended through the dial 2, the roller 14 riding over a stationary cam 15, mounted in the frame of the machine. The roller 14 remains in engagement with the cam 15 while the operations of emplacing the bottom within the

tube are being performed. The jaws 7 are thereafter returned to their normal position by springs 16 which are placed in the elongated slots 10 in the jaws 7.

5 Slidably mounted in the sleeve 13 is a plunger 17 to the top of which is attached a die 18 having a concave working face. The face of the die 18 is adapted to co-act with a die (not shown) having a working face of reverse curvature, the flat disk-like bottom 6 being clamped between the two dies and distorted thereby decreasing its diameter, whereby it may be readily placed within the open end of the tube 3.

10 15 The particular construction of the dies and their relation to each other form no part of the present invention and are specifically described in my application, Serial Number 793,978 filed Oct. 8, 1913.

20 25 The means for directing the compressed fluid medium against the inner surface of the bottom of the finished receptacle consists broadly of two tubes 20 and the necessary connections to supply the compressed fluid thereto. The tubes 20 are, as shown, rectangular in cross-section for convenience of construction and rest in substantially U-shaped grooves 22' cut in the mandrel at diametrically-opposed points (see Fig. 3), 30 although this construction is not essential since the tube may rest against the outer peripheral surface of the mandrel if the same be of a sufficiently small diameter so that the ends of the tubes 20 will not prevent the tubes from being slipped over the mandrel. The upper ends of the tubes 20 are open and are united by an annular ring 21 which rests in a slot 22 cut in the top of the mandrel, with the upper edges of the tubes 40 45 50 55 60 65 70 75 80 85 90 95 100 105 110 115 120 125 130 flush with the top of the mandrel, so that there will be no interference with the proper operation of the jaws 7 of the expanding die or chuck. The lower ends of the tubes 20 are closed and are connected together by means of a ring 23 of larger diameter than the ring 21 and of a size to permit the same to readily slip over the top of the mandrel 1, the ring being held in place between the flange 4 of the mandrel and the base or collar 5.

The cross-sectional area of the ring 23 is enlarged for substantially half of its circumference and is provided with an air passage or conduit 24 which communicates with the lower ends of the tubes 20 through a port 25. Preferably integral with the ring 23 and located half way between the two ports 25, is a hollow pipe or conduit 26. This pipe is L-shaped as shown in Fig. 4, and communicates at its free end with the hole 27 in the dial 1. The other end of the hole or opening 27 is brought into communication by the intermittent rotation of the dial with a pipe 28, which is fastened to the frame of the machine and is provided with

a gasket 29 which prevents leakage of the compressed fluid between the pipe and dial 1. The pipe 28 is connected to any suitable reservoir of compressed air (not shown).

Directly over the upper open ends of the tubes 20, the jaws 7 of the expanding chuck and the plate are formed with circular recesses 30 which direct the passage of the compressed fluid from the tubes 20 to the lower face of the die 18. The die 18 is provided with four openings 31 directly above the ends of the bolts 8, the openings 31 being of sufficient diameter to permit the compressed air to readily pass through the space between the walls of these openings and the sides of the bolts. During the emplacing of the bottom 6 in the end of the tube 3, the die 18 is raised above the edge of this tube by a mechanism (not shown). In this position of the die, the openings 31 are liable to become clogged by paper chippings, or from various other causes. When the plunger then drops to the position shown in Figs. 1 and 3, these openings, if clogged, are automatically cleaned by the ends of the bolts 9 passing into the same, the clearance between the walls of the openings 31 and the bolts 9 being sufficient to permit a sufficient quantity of compressed air to pass around the bolts which will therefore be directed against the bottom of the receptacle and remove the same in a practical and expeditious manner. Pins 32 threaded into the lower face of the die 18 slide in vertically-arranged cylindrical recesses in the mandrel 1 and prevent the plunger 17 from turning, thus maintaining the openings 31 in the die 18 directly above the bolts 9.

The operation is briefly as follows: After the bottom 6 has been placed in the end of the tube 3 by the die 18 and the parts co-acting therewith (not shown) and the edges of the tube projecting beyond the bottom 6 have been crimped or curled inwardly as shown in dotted lines in Fig. 1, the dial 3 then receives a further partial rotation which is sufficient to clear the roller 14 from the end of the stationary cam 15. The sleeve 13 then drops by gravity and the jaws 7 of the expanding die or chuck are returned to their normal position by the tension of the springs 16. The finished receptacle is then ready to be removed. As the dial 3 is turned to its last-mentioned position, the hole 27 in the dial 3 is brought into alignment with the pipe 28 and the compressed fluid may then pass through the pipe 26 and the conduit 24 in the ring 23 through ports 25 to the tubes 20. In this position of the dial, the die 18 is in the position shown in Fig. 2 and the compressed fluid then passes through the recesses 30 in the jaws 7 and plate 8 to the lower face of the plunger die 18. The compressed fluid then passes through the spaces provided between the walls of the openings

31 and the bolts 9 and is directed against substantially the entire inner surface of the bottom 6, the pressure of the fluid blowing the finished receptacle off the mandrel. 5 When it is desired to remove the tubes 20 to clean them, if the same should become clogged, the plunger 17 and the jaws 7 are first removed, after which the tubes 20 and their supporting structure may be readily 10 removed from the mandrel without taking the mandrel from the base, so that once the mandrel has been properly set on the dial its position is not interfered with.

Having described my invention, I claim:—

15 1. In a bottoming machine a rotating dial, a mandrel on said dial over which is positioned the body of the receptacle, means for directing a compressed fluid medium against the bottom of the receptacle to remove the same from the mandrel when said mandrel reaches a determined point in its path, said means comprising a structure removably supported on said mandrel.

2. In a bottoming machine, a mandrel 25 over which is positioned the body of the receptacle, means for directing a compressed fluid medium against the bottom of the receptacle to remove the same from the mandrel comprising a plurality of tubes arranged around said mandrel, and means supported by said mandrel for uniting the ends of the tubes, said tubes and means forming a unitary structure removable from the mandrel.

35 3. In a bottoming machine, a rotating dial, a mandrel fastened to said dial over which is positioned the body of the receptacle, means for directing a compressed fluid medium against the bottom of the receptacle to remove it from the mandrel comprising a plurality of tubes mounted on said mandrel and communicating with openings in the dial, and means for admitting compressed fluid to said opening at a predetermined period in the rotation of the dial.

4. In a bottoming machine, a mandrel over which the body of the receptacle is positioned, means for directing a compressed fluid medium against the bottom of the receptacle to remove it from the mandrel comprising 50 a plurality of tubes mounted on said mandrel, a ring for connecting said tubes together at one of their ends, said ring having a conduit therein communicating with each of said tubes and a pipe connected to said 55 last-named ring and opening into said conduit.

5. In a bottoming machine, the combination of a mandrel over which the body of the receptacle is positioned, a solid circular 60 die mounted on said mandrel and adapted to fit within the open end of the tube, means for directing a compressed fluid medium against the bottom of the receptacle to remove it from the mandrel comprising 65 passages arranged longitudinally of the mandrel, said die having openings therein to distribute the air against the inner surface of the bottom of the receptacle.

6. In a bottoming machine, the combination of a mandrel over which the body of the receptacle is positioned, a solid circular die 70 mounted on said mandrel and adapted to fit within said body portion of the receptacle, and an internal expanding die 75 mounted on said mandrel with means for directing a compressed fluid medium against the bottom of the receptacle comprising passages arranged longitudinally within the mandrel, said expanding die and circular die 80 having openings therein through which the compressed fluid medium is directed against the bottom of the receptacle.

In witness whereof, I subscribe my signature, in the presence of two witnesses.
